Primary Examiner — Jasmine Mlinarcik*Assistant Examiner* — James P McKane(74) *Attorney, Agent, or Firm* — Dunlap Bennett & Ludwig, PLLC(57) **CLAIM**

The ornamental design for an exoskeletal suit, as shown and described.

DESCRIPTION

FIG. 1 is a perspective view of an exoskeletal suit, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is an enlarged perspective view of the claimed portion of the hand component of FIG. 1.

The broken lines shown in the drawings depict portions of the exoskeletal suit that form no part of the claimed design.

1 Claim, 7 Drawing Sheets(56)
